(57) **CLAIM**

The ornamental design for the fourteen-way top cuff for a golf bag, as shown and described.

DESCRIPTION

FIG. 1 is a top perspective view of the fourteen-way top cuff for a golf bag showing my new design;

FIG. 2 is a front elevation of the top cuff;

FIG. 3 is a side elevation view of the top cuff;

FIG. 4 is back elevation view of the top cuff;

FIG. 5 is top view of the top cuff; and,

FIG. 6 is a bottom view of the top cuff.

The broken line showing of outer rim in the views is for illustrative purposes only and forms no part of the claimed design.
